UNITED STATES PATENT OFFICE.

LORD A. STITH, OF PLUM LICK, KENTUCKY.

CAR-COUPING.

SPECIFICATION forming part of Letters Patent No. 257,780, dated May 9, 1882.

Application filed February 4, 1882. (No model.)

To all whom it may concern:

Be it known that I, LORD A. STITH, of Plum Lick, in the county of Montgomery and State of Kentucky, have invented a new and 5 useful Improvement in Car-Couplers, which improvement is fully set forth in the following specification and accompanying drawings, in which—

Figure 1 is a perspective elevation of the 10 coupler. Fig. 2 is a top view of one of the improved draw-bars, and Fig. 3 represents a modified form of securing spring to the draw-bar.

The object of this invention is to provide an 15 improved coupler for cars.

Referring to the accompanying drawings, A represents one of the draw-bars containing the latches or hooked lever, and L the draw-bar for the opposing car, containing the mouth 20 or socket for the hooked bars of the first-named draw-bar.

The draw-bar A is pivoted at the rear end at B to the car, and a guard, B', is placed under the forward end of the car for supporting the 25 forward end of the draw-bar. This guard is sufficiently wide to permit the draw-bar to have lateral play. The draw-bar is in the form of a shell or hollowed, A', within.

C represent latches secured within and to 30 the shell at their rear ends with a wedge, E, between them, the cross-pin F being designed to hold the latches in position. The latches C have wide leaves, which project out from the sides of the shell A.

At the forward end of the draw-bar the leaves of the latches are narrowed down, forming a neck, C', which passes through the contracted or narrow mouth A' of the draw-head A.

40 Outwardly-projecting hooks D are formed on the latches C, as shown. These hooks D extend out a sufficient distance, so that when the latches are compressed, as shown in Fig. 2, the points of the hooks will be flush with the outside of the draw-head. The latches are made of spring metal; or, if preferable, each latch may be independently hinged at the rear end to the shell or draw-bar, and a suitable spring placed between them to keep them dis- 45 tended in the position shown in Fig. 1.

G represents a semicircular vertical groove cut in the inner surface of each jaw or latch, so as to perform the office of a link when it is desired to couple with the common draw-bar.

H represents a lever having a loop, which is passed over the shell or draw-bar A and hinged at one side to the shell at I. The loop is of sufficient length that when the jaws or latches are distended the leaves of the latches 60 will rest against the ends of the loop.

It will be observed that if the outer end of the lever H, which extends to the side of the car, is pushed to the rear the loop will press the leaves inwardly, closing the latches, as 65 shown in Fig. 2.

A suitable lever, K, hinged to the bracket K' on the under side of the car, and having a connecting-rod, J, provides a ready means for manipulating the jaws of the coupler.

The opposite car has the draw-bar L, which is provided with a head, M, and mouth N of sufficient dimensions to receive the contracted head A. The sides of the mouth are flaring to receive the jaws D, and suitable hooks or 75 ledges O are formed within the mouth on each side to receive the hooks or jaws D.

G is a perforation to receive a pin for use when it is desired to couple with a car having the old-style draw-bar and link.

80 The operation is as follows: The jaws D in Fig. 1 are in proper position to couple with the approaching draw-head. As the jaws enter the mouth N they are pressed together, and the head A' also enters the mouth N, when the jaws D hook on the ledges O. To uncouple, the lever K is pushed to the rear, which again presses the jaws together and releases their hold from the ledges O.

In Fig. 3 I represent an improved manner 90 of securing a spring to the draw-bar. P is an elliptical spring passing transversely through the aperture Q of the draw-bar, and secured to the draw-bar by means of the bolts R. B is the ordinary draw-bar pin.

I am aware it is not new to provide one draw-bar with draft-hooks and the opposite draw-bar with a mouth having ledges or shoulders to receive the draft-hooks, and I do not claim this, broadly.

Having described my invention, what I claim is—

In car-couplers, the draw-bar A, having within a recess, Δ' , containing the latches C, provided with leaves or wings which project through the sides of the draw-bar, and with jaws D, which project from the forward end, and looped lever H, in combination with the draw-bar L, having the mouth N, provided

with ledges or shoulders O, substantially as herein set forth.

In testimony that I claim the foregoing I have hereunto set my hand this 30th day of January, 1882, in the presence of witnesses.

LORD A. STITH.
